UNITED STATES PATENT OFFICE.

FRANZ A. BOEDTCHER, OF BERGENFIELD, NEW JERSEY, ASSIGNOR TO OTIS ELEVATOR COMPANY, OF JERSEY CITY, NEW JERSEY, A CORPORATION OF NEW JERSEY.

DOOR OPERATING AND LOCKING DEVICE.

Application filed August 30, 1924. Serial No. 735,094.

This invention relates to apparatus for the operation and locking of the floor doors installed at the various floors of an elevator shaft.

5 It is desirable in this type of door to provide simple and efficient means for sliding the door from open to closed position and vice versa, while an elevator is at a corresponding floor, but it is also essential that these doors be 10 so locked that when an elevator leaves the floor, they cannot be opened by a prospective passenger on the outside of the door to permit of accident hazards.

In accordance with the present invention, 15 I provide a double safeguard against the leaving of floor doors unlocked and accomplish this result through the employment of improved mechanism. In its preferred practical form, the invention embodies a toggle, 20 the terminal of one link of which is pivoted to the door casing and the other link of which is pivoted intermediate its ends to the door. Adjacent the end of the link, which is pivoted to the door, is a suitable handle by means of 25 which the toggle may be flexed to impart sliding movement to the door. Associated with the door is a latch and on the manually operable link adjacent the handle is a stop or keeper, preferably a stepped keeper, comprising a plurality of shoulders or stops and with these shoulders the latch is adapted to 30 cooperate.

When the toggle is flexed to close the door and approaches a position of alinement of 35 these links, the latch is adapted to traverse the shoulders of the keeper in succession and if the door is completely closed the latch will engage with the last step to lock the door in closed position. If however the door is not 40 completely closed, the latch will engage with one of the other shoulders so that even though the door is not wholly closed, it will nevertheless be locked against further opening. I also associate with the toggle as a precautionary 45 measure a switch which is included in the elevator controlling circuit or some other circuit on which the operation of the elevator is dependent and so organize the parts that this switch will not be closed unless the toggle 50 is in a position to fully close the door. I thus not only provide for a locking of the door against opening from either a closed or partially closed condition, but also make it impossible for the elevator to leave the floor

until the door has been fully closed and 55 locked.

In my prior Patent No. 1,413,570, issued April 25, 1922, combination door locking and circuit controlling device, these same general conditions are prevalent, but the 60 present invention is an improvement on the prior one, is more easily operable by the car operator and is found to give better results in practice.

Aside from the precautionary measures 65 which have been adverted to, the invention further embodies the utilization of a cushioning device cooperating with the toggle to preclude slamming of the door.

Features of the invention, other than those 70 specified, will be apparent from the herein-after detailed description and claims, when read in conjunction with the accompanying drawing.

The accompanying drawing illustrates one 75 practical embodiment of the invention, but the construction therein shown is to be understood as illustrative, only, and not as defining the limits of the invention.

Figure 1 shows the present invention as- 80 sociated with an elevator door. In this figure the parts are shown in full lines in the positions which they occupy when the door is closed and in dotted lines the position which they occupy when the door is partially 85 open.

Referring to the drawing, 1 designates a sliding shaft door of an elevator installation. 2 is a toggle comprising two links 3 and 4 pivoted together at the elbow of the toggle 90 at 5. The free end of the link 3 is pivoted to the door casing at 6, while the link 4 is pivoted intermediate its ends as at 7 to a plate 8 fixed on the door 1. At the free end of the link 4 is provided a handle 9 adapted to be grasped by the operator who applies force thereto for the purpose of flexing the toggle. When the toggle is in distended condition with the links 3 and 4 in substantial alinement, the door will be closed, but if 100 force is applied to the handle to flex the toggle, the door will be slid into an open position during which travel the links of the toggle will partake of the dotted line positions shown in Figure 1. Through the operation 105 of the toggle, the door may thus be slid from open to closed position and vice versa, a stop 10 mounted on the plate 8 serving to preclude

overtravel of the toggle during the closing of the door.

Mounted on the plate 8 is a latch or detent 11 pivoted at 12 to the plate and cooperating with a limiting pin 13 which works in a slot 14 in the latch. The latch is pivoted to the plate 8 off center and thus normally gravitates into a position wherein the upper end of the slot 14 will bear against the limiting pin 13. A finger piece or knob 15 formed on the latch allows of its ready manipulation. On the link 4 of the toggle and mounted in such position as to be cooperable with the latch is a keeper 16, shown as formed with 15 two shoulders 17 and 18 although more than two shoulders may be provided.

The parts are so assembled that as the toggle moves from the position shown in dotted lines in Figure 1 to the distended position, 20 the keeper will be brought into engagement with the inclined surface 19 of the latch and will force the latch back against gravity until the keeper passes by the nose of the latch, during which operation the shoulders 18 and 25 17 will pass the nose of the latch in succession. If closing movement of the door ceases after the nose of the latch has passed the shoulder 18, but before it has reached the shoulder 17 the latch will engage with the shoulder 18 30 and will lock the door against the opening by a person on the other side of the door, so that even though the elevator proceed leaving the door slightly ajar, the door will be left in a safe condition. However 35 to insure that the door be entirely closed before the elevator leaves the floor, I preferably associate with the toggle a switch 20. This switch is mounted on the door casing and a controlling arm 21 of the switch secured to the toggle by means of a link 22. The switch is so constituted that it will be 40 closed only when the toggle is in a position to fully close the door, while in all other positions the switch will be open. This switch 45 is included in an electric circuit which controls the operation of the car so that unless the door is fully closed, the switch will be open and the car cannot leave the floor.

To preclude slamming of the door or the 50 toggle, I preferably also associate with said toggle a cushioning device in the form of a piston 23 pivoted to a bracket 24 mounted on the link 3. This piston is operable within a cylinder 25 pivoted to the door casing at 55 26. In practice, the cushioning device may be pneumatically or spring controlled or a combination of these two, but in either event its function is to check the movement of the toggle as it approaches its maximum destination so that it will not come to an abrupt stop 60 against the stop 10. This construction obviates slamming of the toggle and consequent slamming of the door.

To open the door, the car operator places 65 the tips of four fingers on the upper surface

of the handle 9 and with the thumb of the same hand presses the finger piece 15 upwardly to disengage the latch from the keeper while simultaneously applying a downward pressure on the handle 9. The keeper will thus be released and the toggle flexed to slide the door into open position. To close the door, the direction of pressure on the handle 9 is reversed, but no attention need be paid to the latch since, acting under the 75 force of gravity, it will automatically re-engage the keeper and lock the toggle against inadvertent flexing.

An important feature inherent in the use of the latch and keeper in connection with 80 the toggle is that it will positively stop rebound of the toggle and this is important as such rebound would otherwise invariably leave the door in slightly open condition. This cannot possibly occur when the gravity 85 latch is employed.

The latch 11 is preferably a gravity latch as described, but, if desired, I may employ a spring actuated latch. Accordingly, the invention is to be understood as not limited to 90 the details of construction described but is to be construed as broadly novel as is commensurate with the appended claims.

Having thus fully described the invention, what I claim as new and desire to secure by 95 Letters Patent is:

1. An assembly of the character described embodying a door mounted for sliding movement, a toggle, one end of one link of which is pivoted to a relatively stationary pivot and the other link being pivoted to the door, a shoulder formed on the last mentioned link, and a latch mounted on the door and adapted to automatically gravitate into locking relation with the shoulder of said link as the toggle is moved into distended condition to close the door. 100

2. An assembly of the character described embodying a door mounted for sliding movement, a toggle, one end of one link of which is pivoted to a relatively stationary pivot and the other link being pivoted to the door, a shoulder carried by the last mentioned link and a latch mounted on the door and positioned to automatically come into locking relation with the shoulder of said link as the toggle is moved into distended condition to close the door. 110

3. An assembly of the character described embodying a door mounted for sliding movement, a toggle, one end of one link of which is pivoted to a relatively stationary pivot and the other link being pivoted intermediate its ends to the door, a succession of shoulders formed on the last mentioned link, and a latch mounted on the door and adapted to automatically come into locking engagement with said shoulders in succession as the toggle is moved into distended condition to close the door. 120

4. An assembly of the character described embodying a door mounted for sliding movement, a toggle comprising two links, the contiguous ends of which are pivoted to one another, a pivot for securing the free end of one link to a relatively fixed support, a pivot securing the other link to the door, a handle and a stop on the last mentioned link in proximity to one another, both the handle and stop being rigid with respect to said link, and a latch carried by the door and

adapted to automatically and positively engage the stop when the door is closed to lock the toggle against flexing, said latch being positioned to be manually released by the 15 hand of an operator while said hand is gripping the handle, to permit opening of the door.

In testimony whereof I have signed the foregoing specification.

FRANZ A. BOEDTCHER.
